US00D895914S

(12) **United States Design Patent** (10) Patent No.: **US D895,914 S**
Blumer et al. (45) Date of Patent: ** Sep. 8, 2020

(54) **VACUUM SYSTEM**

(71) Applicant: **The Charles Machine Works, Inc.**,
Perry, OK (US)
(72) Inventors: **B. Zac Blumer**, Stillwater, OK (US);
Benjamin S. Burkhart, Stillwater, OK
(US); **L. Shane Ingram**, Perry, OK
(US); **Levi J. Krutzfeldt**, Perry, OK
(US); **Jim Lee**, Yale, OK (US)

(73) Assignee: **The Charles Machine Works, Inc.**,
Perry, OK (US)

(**) Term: **15 Years**

(21) Appl. No.: **29/637,279**

(22) Filed: **Feb. 15, 2018**

(51) LOC (12) Cl. **15-05**

(52) U.S. Cl.

USPC **D32/21**

(57) **CLAIM**

The ornamental design for a vacuum system, as shown and described.

DESCRIPTION

FIG. 1 is a front right perspective view of a vacuum system, showing our design.

FIG. 2 is a front left perspective view thereof.

FIG. 3 is a rear right perspective view thereof.

FIG. 4 is a rear left perspective view thereof.

FIG. 5 is a right side elevation view thereof.

FIG. 6 is a left side elevation view thereof.

FIG. 7 is a front elevation view thereof; and,

FIG. 8 is a top plan view thereof.

The broken line showing of elements is included for the purposes of illustrating portions of the vacuum system and form no part of the claimed design.

1 Claim, 8 Drawing Sheets
